UNITED STATES PATENT OFFICE.

CHARLES P. STANBON, OF LYNN, MASSACHUSETTS, ASSIGNEE, BY MESNE ASSIGNMENTS, TO UNITED SHOE MACHINERY COMPANY, OF PATERSON, NEW JERSEY, A CORPORATION OF NEW JERSEY.

WELT-CUTTING MACHINE.

1,115,123.

Specification of Letters Patent. Patented Oct. 27, 1914.

Application filed March 31, 1906. Serial No. 309,109.

To all whom it may concern:

Be it known that I, CHARLES P. STANBON, a citizen of the United States, residing at Lynn, in the county of Essex, State of Massachusetts, have invented an Improvement in Welt-Cutting Machines, of which the following description, in connection with the accompanying drawings, is a specification, like letters on the drawings representing like parts.

My invention relates to boot and shoe machinery, more particularly to machines for slitting, grooving, beveling or skiving welts.

In the manufacture of welted boots and shoes, the welts are usually supplied to the trade in rolls of or approximating the desired widths and thicknesses but not otherwise prepared for use.

One of the objects of my invention is to produce a machine for preparing a welt for use upon the shoe and to that end comprises a machine adapted to receive a welt from the roll or a reel upon which the roll is placed and to chamfer or bevel the edge of the welt that is to rest or fit against the shoe upper, to groove the under side to receive the stitches of the inseam, to skive the surface of the welt uniformly at desired depth or taper it toward either edge, and to cut lateral or transverse slashes or slits in its surface, adjacent one edge and suitably spaced one from another, to permit stretching or contracting said edge as the welt is curved or shaped to the edge of the sole with the body of the welt approximately in the plane of the insole. Suitable feeding mechanism is provided for presenting the welt to the action of the cutting tools and for thereafter reeling it up in a suitable manner for subsequent use and to facilitate handling. By providing a machine to secure these results automatically, greater uniformity is obtained in the completed or prepared welt than when the operations are manual, and furthermore, a saving of labor, time and expense results. These and other objects and features of my invention, however, will be best understood and appreciated from the following description, when considered in connection with the accompanying drawings, of a machine typifying one embodiment of my invention and se-

lected for purposes of illustration, the scope of the invention being more particularly pointed out in the appended claims. 55

Referring to the drawings: Figure 1 is a front elevation of a complete machine selected for illustration; Fig. 2, an elevation of its left side; Fig. 3, an enlargement of the upper part of the machine illustrated in Fig. 1, to show the welt cutting and feeding mechanism; Fig. 4, a similar and partially sectional detail of the left side of the machine; Fig. 5, a horizontal section taken on the line 5—5 Fig. 4; Fig. 6, a vertical section on line 6—6 Fig. 3 from the left; Fig. 7, a plan and partial horizontal section of the welt guiding frame to show the movable guide and the adjusting mechanism of the edge beveling knife; Fig. 8, a horizontal section on line 8—8, Fig. 4; Fig. 9, a vertical sectional detail through the axis of the reel shaft and friction pulley, and Fig. 10 a view of the finished welt.

In the embodiment of my invention herein illustrated, see Figs. 1 and 2, the machine is provided with a usual column, 1, and head, 2, on which is secured a supporting frame 3, for the welt cutting and feeding mechanism. This frame has uprights, 4 and 5, provided with suitable bearings for horizontal feeding wheel shafts, 6 and 7, arranged one above the other. Upon the front end of each of these shafts is a feeding wheel, respectively numbered, 8 and 9, 85 in the drawings (see Figs. 2 and 3); the upper wheel 8, however, also constituting a welt supporting wheel to sustain the welt, 10, as it is subjected to the action of the slitting and skiving tools presently to be described. The edge of the wheel 8, which will be hereinafter denominated as the welt supporting wheel, may be made smooth or it may be roughened, while that of the lower or feeding wheel 9, is made rough or is milled to cause it to grasp or bite upon the welt, 10, which is to be passed over the top of the welt supporting wheel and around between said wheels and to be fed by their rotation (Fig. 1). To secure such feeding, 100 said wheels, 8 and 9, are rotated in opposite directions by gear wheels, 11 and 12, respectively mounted on the rear ends of said shafts 6 and 7 and in mesh with one an-

other, the lower shaft, 7, having immediately exterior to said gear wheel, 12, a worm gear 13, which is rotated by the worm 14 on a counter shaft 15. This counter shaft, 15, 5 journaled in suitable bearings in the frame 3, has a pulley, 16, on its right end, which is connected by a belt, 17, to a drive wheel, 18, on the corresponding end of a drive shaft, 19, near the base of the column, the rotation 10 of which rotates the worm and the connected gears, to cause the feed wheels to rotate in opposite directions and present the welt to the action of the cutting tools. The opposite end of said drive shaft, 19, has the usual fast and loose pulleys, 20, 21, adapted 15 to be driven from a power shaft in the usual manner.

To permit separation of the welt supporting and feeding wheels, or depression of the 20 feeding wheel to facilitate insertion of the welt between it and the welt supporting wheel, and that the latter may be automatically and vertically adjustable to adapt 25 itself to different thicknesses of welt, I have, in the present instance, (Figs. 4 and 8), mounted the feeding wheel shaft, 7, to swing or oscillate in a vertical plane, by pivotally supporting its rear bearing and by making the bearing for the front end reciprocatory. 30 As herein shown (Figs. 4 and 8), the rear oscillatory mounting comprises a trunnioned sleeve, 22 (Fig. 8), which is pivoted intermediate its ends by horizontal supporting screws, 23, tapped through the upright 5, 35 and held by clamping nuts 23^a, the pointed ends 24, of said screws engaging conical recesses 25, formed in said sleeve 22. Said upright 5 is provided with a vertical and transverse recess, 26, to receive said shaft, 7, 40 and its bearing sleeve, 22, and to permit such vertical oscillations thereof as may be required. To permit the front end of said shaft 7, with its feeding wheel, 9, to be elevated or depressed, the upright, 4, is provided with a vertical recess, 27, (Fig. 4), 45 transversely arranged to receive a box, 28, loosely mounted on said shaft, 7, and forming a vertically movable bearing therefor. This box, 28, is square in cross section, its 50 vertical sides, 29, Fig. 3, bearing against the vertical walls, 30, of said recess, 27, which act to guide said box in its movements while confining it and thereby said feeding wheel, 9, to swing in a vertical plane passing 55 through the axis of the upper shaft, 6, so that said feeding wheel, 9, is always presented in proper relation to the coöperating welt supporting wheel 8 for feeding purposes. For normally holding said box 28, 60 elevated with the feeding wheel in feeding relation to the welt supporting wheel, 8, a coil spring, 31 (Fig. 4), is interposed with its upper end bearing against said box and its lower end seated in a vertical socket or 65 circular opening, 32, formed in said up-

right, 4. By this arrangement of the feeding wheel shaft its feeding wheel, 9, may be and is automatically depressed by the thickness of the welt or elevated by the action of the coil spring, 31, so that 70 the feeding mechanism is adapted for use with any of the usual thicknesses of welt, the feeding action not being interrupted by any variation thereof nor requiring any other adjustment, the regulation being entirely automatic. 75

In inserting or positioning the welt between the welt supporting and feeding wheels, 8 and 9, the feeding wheel may be positively depressed to facilitate placing the 80 welt therebetween. The means for securing this movement, in the present instance, comprises a horizontal pivoted, cylindrical rod, 33 (Figs. 3 and 4), having a rectangular recess, 34 (Fig. 3), in its periphery, the flat 85 or slab face, 35, of which, bears upon the upper horizontal face of the square box, 28. The outer end of this depressing rod, 33, is provided with a crank arm or handle, 36, by which it may be turned or rotated in its 90 bearings, thereby, through the action of the slab face, 35, on the face of said box, positively depressing the latter, 28, and consequently said feeding wheel, 9, sufficiently, to permit ready insertion or removal of the 95 welt. By returning said handle 36, to its normal, herein shown as vertical position, the coil spring 31, is permitted again to elevate said box 28 and the feeding wheel to its feeding position. 100

For supporting the roll of welt as received from the trade and to present the strip to the feeding mechanism, by which it is brought into cutting relation to the cutting tools, I have, in the present instance, 105 provided the following instrumentality: Mounted at the base of the column (Figs. 1 and 2) upon a horizontal stud, 37, is a core or quill 38, upon which are two disks, 39, 40, the outer one, 39, being removable to permit 110 the roll of welt to be centered on said quill after which said outer disk 39, is again secured in place in suitable manner to hold the roll thereon. The quill and the disks being loosely mounted on said stud, the roll of 115 welt is readily unwound, its free end being carried up over a guide roller, 41 (Fig. 1), and a guide 42, respectively carried or formed upon supporting arms, 43, 44, secured to the frame 3, and column 1. The 120 welt is next carried through a welt guiding frame or trough, 45 (Figs. 3, 6 and 7), which is provided with a horizontal stud, 46 (Fig. 6), normally secured or retained in place within a clamping or split head, formed 125 upon the upright 4, jaws 47, of which are clamped by means of the screw bolt 48, and by means of which said welt guiding trough may be removed when desired. Referring to Figs. 3 and 6, said guiding trough has an 130

upper horizontal or overhanging wall, 49 (Figs. 3 and 6), upon which is supported a depending flat spring 50 and vertical adjusting screw 51, by which the tension of the spring upon the welt passed beneath it and pressed by it against the bottom plate or supporting wall 52, of the guiding trough may be varied as desired or required. To adapt the guiding frame to receive welts of different widths, its front edge is provided with an adjustable edge gage or guiding plate, 53. In the present instance, this plate is carried or supported on a horizontal rod, 54 (Fig. 7), which is loosely and slidably mounted in said guiding trough (Figs. 3, 6 and 7). Said rod, 54, extends through said frame and its outer end is threaded to receive a nut, 55, between which and said trough a coil spring, 56, encircling said rod, 20 is interposed and normally acting to hold said gage or guiding plate, 53, inward (Figs. 6 and 7). The opposite or front end of this gage supporting rod 54, is provided with a handle, 57, to facilitate pulling the gage forward in inserting the welt. This gage is provided with a horizontal portion, 58, to rest upon the bottom plate of the trough, with an inner vertical edge, 59, to bear upon the edge of the welt, and an outer turned down portion, 60, drilled to receive the supporting rod and to rest upon the outer edge, 61, of the guiding trough when in its normal position. This guiding trough carries the edge beveling or feathering tool, 62 (Figs. 3, 35 6 and 7), vertically mounted in the bottom plate of said trough and held in adjusted position by means of the set screw 62^a.

The welt grooving and skiving tools or knives, 71 and 72, and the foot plate, 70, are adjustably mounted in a vertically extended arm, 63 (Figs. 3 and 4), of the upright, 4, a portion of which is offset (Fig. 4) from said upright to permit the tools to act upon the welt fed over the welt supporting 45 wheel 8 which, as described, is mounted exterior to said upright 4. This arm, 63, is provided with rectangular vertical, peripheral grooves or recesses, 64, 65, 66, in its front and back faces (see Figs. 4 and 5), 50 respectively to receive the carriers 67, 68 and 69, for the foot plate, 70, the grooving tool, 71, and the skiving tool, 72. That these carriers may be separately adjusted vertically, each has a vertical adjusting stud or guide pin 73, (Fig. 4), threaded at its lower end into the top of its carrier, the upper ends of the guide pins, extending vertically through perforations or openings in the upper walls 55 74 (Fig. 4), of said recesses, and a lifting plate, 75, and having squared heads, 76, bearing upon the upper surface of said lifting plate. For normally holding these pins and their tool carriers depressed, each pin is encircled by a coil spring 77, interposed between said walls, 74, and the upper

face of the carriers. Each of said carriers is square in cross section (Fig. 5) the inner faces of each bearing against and adapted to slide in the vertical rectangular recess in which it is mounted. These carriers are retained in place by means of the face plates, 78, 79, secured to the opposite lateral faces of said arm, 63, respectively. This arrangement permits independent adjustment of each carrier and its tool, the squared or otherwise shaped heads of the adjusting pins being adapted to receive a key, wrench, or other tool for screwing them up or down to adjust the tools as desired. In order that said carriers and their tools may be simultaneously elevated or depressed, said vertical arm, 63, in the present instance, has a vertical extension, 80 (Figs. 1 and 3), upon which is pivoted a handle lifting lever, 81, its inner forked end 82, being pivoted to a vertical ear, 83, on said lifting plate, 75. By elevating or depressing the handle lever, 81, and said lifting plate, 75, the carriers and tools carried thereby are simultaneously lowered or elevated. For holding or locking the lifting plate elevated against the action of said springs, 77, said lever, 81, is provided with a spring controlled latch lever, 84 (Fig. 3), pivoted at 85, on said handle, the inner or latching end 86, of said latch lever, 84, bearing on a cam shaped lug, 87, formed on said extension, 80, the lug having a vertical drop or notch, 88, into which said inner end of the latch is moved by its spring, 89, when the handle, 90, of the lifting lever is sufficiently depressed or the lifting plate correspondingly elevated. By this arrangement a reverse movement of said lever is prevented, until in grasping the handle, 90, of the lifting lever, the outer end of the latch lever, 84, is depressed, raising its latching end 86, out of engagement with said notch, 88, thus permitting elevation of said lifting lever, 81, so that the lifting plate and tools carried thereby may be lowered or dropped into operative position.

The foot, 70 (Fig. 3), is recessed into and secured at one side of its carrier, 67, and is curved downwardly and extended horizontally to bear upon the upper face of the welt for holding it against the welt supporting wheel 8. The tubular grooving tool or cutter, 71, is adjustably secured to its carrier, 68, preferably by clamping plates, 91 (Figs. 3 and 4), and the clamping screw, 92, the grooving tool being thereby presented at a suitable angle to the upper or what in the finished shoe will be the bottom of the welt, for grooving it and to carry off through its axial through and through opening the material cut from the welt. The skiving tool 72 (Fig. 4), has beveled sides fitting into a dovetail recess or groove formed in the end of a holder, 93, pivoted to the carrier, 69, a

clamping plate, 94, and screw 95, at the outer end of said holder, 93, securing the skiving tool in desired horizontal adjustment. The opposite end of this holder, 93, is pivotally connected to the outer face of the carrier, 69, and is held in desired angular adjustment by the clamping bolt, 96, securing said holder in desired position, the elevation or depression of which varies the beveling action of the skiving tool. To permit vertical adjustment of the carriers 68 and 69, with their tool holders 91 and 93, the face plate 78 is provided with slots 78^a, and the upright 4, with a rabbet 66^a. By this arrangement of the skiving tool, the welt may be tapered or beveled toward either edge as desired or the upper surface skived uniformly at greater or less depth according to the vertical adjustment of its carrier, 69, by means of its adjusting stud or pin, 73.

One important feature of my invention is the slitting tool, 97, or the knife which cuts the incisions or transverse slits or slashes in the bottom surface of the welt which permits the welt being shaped to lie in the plane of the insole. By making incisions in the body of the welt rather than by cutting clear through a strong and durable welt is produced which is readily shaped to lie in the plane of the insole. In the embodiment of my invention herein illustrated (Figs. 3 and 4), this knife is mounted upon a carrier arm, 98, the opposite end of which is pivotally connected at 99, to the base of the supporting frame. The split clamping head, 100, of this carrier is pivotally connected to a link 101 which at its lower end is in turn pivotally connected to a crank pin, 102, on the front end of a horizontal cross shaft, 103, rotated by means of a bevel gear, 104, at its rear end and which is meshed with a similar gear, 105, upon the left end of the counter shaft, 15.

In operation, the rotation of the cross shaft, 103, and its crank pin, 102, produces a rapid oscillatory motion of the slitting knife toward and from the traveling welt, slitting the surface of the welt adjacent its outer edge laterally and periodically, said slit being obliquely cut into the surface of said welt longitudinally of its length, with the length of the slits transverse thereto. The clamping head of the carrier is grooved to receive the beveled sides of the slitting tool or knife, 97, and is provided with a clamping bolt, 106, to hold said tool in place and to permit its adjustment to compensate for wear or to vary the depth of the slit. The cutting edge of the slitting knife is inclined (Fig. 8) so that the slit cut thereby in the welt is deeper at its edge than elsewhere.

The description of the several cutting tools has been taken up in the order in

which they operate upon the welt, continuously fed into cutting relation thereto by the action of the feeding wheels 8 and 9.

By reference to Figs. 1 and 3, it will be apparent that the edge beveling knife, 62, is the first to operate upon the moving welt while it is passing through the welt trough 45. As the welt moves over the inner end of said trough it is subjected to the action of the grooving tool, 71, and then passes onto the welt supporting roll 8, where it is skived by the knife, 72. As the welt is then fed down over the curve of the feeding or supporting wheel, 8, it is slashed or slit by the rapid oscillations of the slitting knife, 97, the convex surface of the welt being more especially adapted to be operated upon than when presenting a flat surface, not only by stretching said surface over the wheel 8, but by curving and feeding the welt down out of the way of said knife 97 as it moves toward and from the welt and thereby permitting a continuous feed thereof. For receiving the welt after it has been suitably cut or shaped and fed through the feeding wheels, the machine, in the present instance (Figs. 1 and 2), is provided with a rotary wheel comprising, for example, a cross frame, 107, secured at its center to the front end of a horizontal shaft, 108, journaled in suitable bearings, 109, of the column, each of the arms having a horizontal pin, 110, upon which the welt is wound as it is fed through the machine, the outer ends of said pins 109 being bent radially outward to hold the welt in place. The rear ends of these pins, 110, being tapped into the arms of the cross, the bent ends 110^a may be turned inwardly toward the axis of the reel permitting ready removal of the loosely coiled welt when desired. When removed the natural tendency of the coil or roll of welt is to collapse, presenting a bundle of suitably cut and loosely arranged welt especially adapted to be tempered or otherwise treated or prepared for use as by immersion in water or otherwise. This arrangement avoids the necessity of unwinding the cut welt from a reel or the like having a core or on which the welt is compactly wound, before it can be properly treated. For rotating this reel and winding up the welt, the opposite or rear end of the shaft is provided with a friction pulley, 111, loosely mounted thereon between a pair of friction disks, 112, 113 (Figs. 2 and 9), the inner one 113, being fast on said shaft, 108, and the outer disk, 112, splined thereto. The end of this shaft, 108, receives a spring washer, 114, and is threaded to receive a clamping nut, 115. By rotating or adjusting this nut, the tension of the spring may be varied to produce the desired friction between the disks and pulley, so that there

may be more or less slip between them. The edge of the pulley is grooved to receive a round belt, 116, connecting said pulley, 111, with a grooved pulley, 117, fast upon the rear end of the lower feed shaft, 7, and rotating it simultaneously therewith. Obviously the disks and shaft connected therewith may be rotated fast or slow as desired, by adjustment of the clamping nut 10 to cause the welt to be reeled fast or slow.

To prevent irregular laying of the welt upon the reel, a reel feeding device is provided comprising, in the present instance, a horizontal reciprocatory slide, 118, slotted at its front end to receive the welt as it passes from the feeding wheels over a guide roller, 119, at the front of the machine. This slide is supported and guided by a suitable hanger or bracket, 120 (Figs. 3 and 4), and at its rear end is provided with a headed horizontal pin, 121, which is received and engaged by the forked end, 122, of an oscillatory lever, 123, pivoted intermediate its ends to an arm, 124, of the supporting frame (Fig. 3). At its upper end said lever, 123, has a longitudinal slot, 123^a, to receive a removable crank pin or screw bolt, 125, on the side of a fixed pulley or wheel, 126, on a short horizontal shaft, 127, journaled in said arm, 124. The inner end of this shaft, 127, is provided with a worm gear, 128, meshing and rotated by a worm, 129, on the welt supporting wheel shaft 6. Rotation of said shaft causes rotation of the worm gear, said pulley, 126, producing an oscillation of the lever, 123, and a reciprocating in and out motion of the welt feeding slide, 118, the gears and motions being timed to cause the welt to be reeled uniformly upon the reel both axially and radially.

In placing the welt upon the machine the outer disk of the quill is removed, the roll of welt placed in position on the sleeve, and the disk again secured in place. The free end of the welt is then carried up over the guide roller, 41, the guide, 42, and through the guiding trough 45, the lower reel turning freely to unwind the welt. The edge gage or guide, 53, is pulled out sufficiently to facilitate placing the welt with its lower face uppermost beneath the spring 50, and to carry it over the welt supporting wheel, 8, the tools being elevated simultaneously by depressing the lever 90, till the welt is in place when it may be raised, the tools then holding the welt in place. The handle 36, of the feeding wheel depressor is next turned to separate the wheels 8 and 9 and permit the insertion of the welt, 10, between them, when it is released. The welt is then carried over the guide roller, 119, and through the slot in the reel slide 118, and its end is secured to one of the horizontal cross pins of the upper reel in any suitable manner as by bending the end of the welt

around it. Each tool is then adjusted to cut as desired, the several adjustments enabling the machine when operated to bevel its inner edge at a desired angle to fit against the upper, to cut a groove of desired depth in the bottom of the welt; to skive the welt uniformly to greater or less depth or to taper its surface toward either edge by respectively raising or lowering the skiving tool and by the angular adjustment of its holder; and lastly to slit the outer welt edge transversely on what will be its bottom in the finished shoe, to permit it to be laid and fitted around the edge of the sole in the plane of the insole but without weakening it by the removal of leather, the finished welt being illustrated in Fig. 10.

Any of these operations may in certain cases be omitted. In the operation of the machine the feeding wheels feed the welt along in cutting relation to the respective cutting tools in the order above mentioned, unwinding the welt from the quill and winding it up on the skeleton reel, the slitting tool being oscillated toward and from the moving welt to cut the slits in manner already described and without checking the travel of the welt.

Claims:

1. A welt cutting machine, comprising a welt guide, a grooving tool, means to feed the welt continuously to said tool to cause the grooving tool to produce a longitudinal groove in the welt in its passage through said guide, a welt slitting tool, and means to cause said slitting tool to act upon and slit the portion of the welt engaged by the feeding means as the latter draws the welt through the machine.

2. A welt cutting machine comprising a grooving tool, a slitting tool and a welt support having stationary and moving portions, said tools being arranged to groove and slit the surface of a welt adjacent its opposite edges while supported on and as it passes over said stationary and movable portions of the welt support.

3. A welt cutting machine comprising a skiving tool, a slitting tool, a moving welt support, and means for feeding a welt strip over said moving support, said tools being arranged to skive and slit said welt as it passes over said support.

4. In a machine for making welts, the combination of a welt support provided with a welt guide, a feathering tool projecting into said welt guide, a grooving tool, a slitting tool, means to reciprocate said slitting tool, and means to feed the welt continuously past said tools, said grooving tool being arranged to act upon the welt and groove it as it passes through said guide, and said slitting tool arranged to slit said welt when engaged by said feeding means.

5. A welt cutting machine comprising a

grooving tool, a skiving tool, means for the independent adjustment of each, and means for simultaneous elevation or depression thereof and for locking said tools in elevated position or dropping them into operative position.

6. A welt cutting machine comprising grooving, beveling, skiving and slitting tools and adjusting means therefor, a moving 10 welt support, means for moving the welt continuously during the action of said tools, and means for causing the slitting tool to act on that part of the welt passing over and while on said moving support.

15. 7. A welt cutting machine comprising in combination a welt support over which the welt is passed, said support having a supporting surface comprising a longitudinally curved portion and a substantially plane 20 portion, a series of stationary cutters acting upon the welt as it passes over the plane surface of said support, and a slit cutter movable in a curved path and co-acting with the curved surface of said welt support to 25 slit the welt.

8. A welt cutting machine comprising in combination a welt support over which the welt is passed, a series of stationary cutters yieldingly supported relative to said support and acting upon the welt as it passes over said support, a movable slit cutter, and means to reciprocate it in a curved path toward and from the support to slit the welt.

9. A welt cutting machine comprising in 35 combination a rotatable welt support, a series of stationary cutters, a slit cutter, means to reciprocate it in a curved path toward and from the welt support, and a feeding device acting upon the welt beyond said 40 tools to draw the welt past said tools.

10. A welt cutting machine comprising in combination a welt support over which the welt is passed, a series of stationary yieldingly supported cutters acting upon the welt 45 as it passes over said support, means for simultaneously moving said cutters out of operative relation with the welt support, a movable slit cutter, and means to reciprocate it in a curved path toward and from the support to slit the welt.

11. In a machine of the class described, the combination, with a welt guide and means for operating on a welt in its passage through said guide, of a feed roll arranged 55 to receive said welt in its passage from said guide, and means for slitting said welt in its passage over said roll.

12. In a machine of the class described, the combination, with a welt guide and 60 means for operating on a welt in its passage through said guide, of a feed roll, and means for slitting said welt in its passage over said roll.

13. In a machine for preparing welts, the

combination of a table for supporting and 65 guiding the welt strip, a pair of feeding wheels between which the welt strip is passed, said feeding wheels being arranged below the welt supporting and guiding table and disposed one below the other to cause 70 the welt strip to have an extended bearing about one of said feeding wheels, means for operating said feeding wheel to feed the welt strip over said table, tools for acting on the welt strip, a presser to press upon the 75 welt strip as it is fed by the feeding wheels, and means for raising the presser and separating the feed wheels to facilitate the introduction and removal of the welt strip.

14. In a machine for preparing welts, the 80 combination of means for supporting and guiding the welt strip, a pair of feeding wheels between which the welt strip is passed and operating means therefor, said feeding wheels having their axes one below 85 the other and both below the line of feed of the welt strip as it passes the welt supporting and guiding means, and tools arranged above the feeding wheels for acting on the welt strip to prepare the same as it is fed. 90

15. In a machine for preparing welts, the combination of a table for supporting the welt strip as it is fed, a pair of feed wheels between which the welt strip is passed, said feed wheels being arranged adjacent one 95 end of and with their axes one below the other and both below the table to cause the welt strip to have an extended bearing about the upper feed wheel, a tool for acting on the welt strip as it is fed, a presser for pressing upon the welt, and means for raising the tool and presser.

16. In a machine for preparing welts, the combination of a table over which the welt strip is fed, an upper and a lower feeding 105 wheel between which the welt strip is passed, the former of said wheels being mounted to receive the welt strip upon the upper portion of its supporting surface adjacent one end of the table, and the other of 110 said wheels having its axis lower than the axis of the upper feed wheel to cause the welt strip to pass about more than a quadrant of the upper feed wheel as it is drawn between the two, a tool for acting upon the 115 welt strip as it is fed, and means for actuating the feeding rolls.

17. In a machine for preparing welts, the combination of welt strip supporting and guiding means, a tool for acting on the welt 120 as it passes along said supporting and guiding means, a feed roll arranged to receive the welt strip and support the same upon its surface after it leaves the welt supporting and guiding means, and a second feed roll 125 coöoperating with the first named feed roll at a portion of its surface below the axis of the first-named roll to cause said strip to

travel over the said supporting and guiding means and about an extensive portion of the first named feed roll.

18. In a machine for preparing welts, the combination of welt strip supporting and guiding means, a tool for acting upon the welt, a feeding wheel below and adjacent said means and about a portion of which the welt is passed, a second feeding wheel below the first-named wheel and between which and the first named wheel the welt travels after passing about an extended bearing portion of the first named feeding wheel, and means for separating said wheels to permit the introduction of the welt strip.

19. A welt preparing machine having, in combination, a work table having a part to engage one edge of the welt, a rod slidably mounted beneath the surface of the table and projecting to the front and to the rear of the table, a movable edge gage mounted on the front of the rod and projecting over the top of the table to bear against the other edge of the welt, a spring connected to the rear part of the rod for holding the edge gage yieldingly against the welt, and means for moving the edge gage against the spring when a fresh welt is to be placed upon the table.

20. A welt preparing machine having, in combination, a work table, a part associated with the table to guide one edge of the welt, a rod slidably mounted beneath the surface

of the table, and a movable edge gage mounted upon the end of the rod and projecting over the top of the table to bear against the other edge of the welt and guide the welt between said part and said movable edge gage.

21. In a welt preparing machine, the combination of a supporting frame, feeding means for taking the welt from a source of supply, tools for acting upon the welt, a reel for winding up the welt after it has been treated by said tools and means to cause the treated welt to be wound on the reel in open spiral coil formation for the passage to all parts of the treated welt of the tempering liquid when the coiled mass is immersed therein.

22. In a welt preparing machine, the combination of a support over which the welt is passed from a source of supply, tools for acting on and cutting the welt as it is passed over said support, feeding means for the welt, and means for winding the cut welt in loose spiral coils in a condition to permit tempering the welt in wound bulk as delivered by the machine.

In testimony whereof, I have signed my name to this specification, in the presence of two subscribing witnesses.

CHARLES P. STANBON.

Witnesses:

SIDNEY F. SMITH,
I. GRACE HOLBROOK.
